UNITED STATES PATENT OFFICE.

DAVID EDWARDS, OF BROOKLYN, NEW YORK.

ROLL-SCREEN FOR WINDOWS.

1,246,570.

Specification of Letters Patent. Patented Nov. 13, 1917.

Application filed October 10, 1916. Serial No. 124,795.

To all whom it may concern:

Be it known that I, DAVID EDWARDS, a subject of the King of Sweden, and a resident of the city of New York, borough of Brooklyn, in the county of Kings and State of New York, have invented a new and Improved Roll-Screen for Windows, of which the following is a full, clear, and exact description.

10 The object of the invention is to provide a new and improved roll screen arranged for convenient attachment to windows without requiring alteration thereof, and adapted to properly screen the window from top to bottom and from side to side to prevent insects from passing into the room and to allow convenient rolling up of the screen for opening or closing the window sashes whenever it is desired to do so. Another object 15 is to combine with the roll screen supports for a window shade and curtain pole.

In order to accomplish the desired result, use is made of brackets adapted to be attached to the window frame at the sides 25 thereof, a spring actuated roller journaled in the said brackets, a screen winding and unwinding on the said roller and provided with spaced battens, one of which is at the bottom of the screen, guideways attached to 30 the sides of the window frame and engaged by the ends of the said battens, manually controlled catches mounted in the ends of the said bottom batten, and keepers in the lower ends of the said guideways and adapted 35 to be engaged by the said catches to lock the screen in lowermost position and with the bottom batten in contact with the sill of the window.

40 A practical embodiment of the invention is represented in the accompanying drawings forming a part of this specification, in which similar characters of reference indicate corresponding parts in all the views.

Figure 1 is a front elevation of the roll screen for windows as applied and with part 45 broken out;

Fig. 2 is a cross section of the same on the line 2—2 of Fig. 1;

Fig. 3 is an enlarged cross section of the 50 casing and one of its supporting brackets attached to the window frame, parts of the bracket being broken out;

Fig. 4 is an enlarged sectional plan view 55 of a portion of the roll screen and one of its guideways, the section being on the line 4—4 of Fig. 1;

Fig. 5 is an enlarged sectional plan view of the lowermost batten, its guideway, and the locking device in one end thereof, the section being on the line 5—5 of Fig. 1; 60

Fig. 6 is a cross section of a modified form of the roll screen as applied; and

Fig. 7 is an enlarged cross section of the bottom batten.

The roll screen in its general construction 65 consists of brackets 10 attached by screws or similar fastening devices 11 to the sides of the window frame or casing 12, and on the said brackets is journaled a spring-actuated roller 13, preferably of the Hartshorne 70 type, and on which winds and unwinds a screen 14 adapted to screen the window from side to side and from the top to the sill of the window frame. The screen 14 is provided at intervals with battens 15, each preferably made of two parts with the screen 75 extending between them, as plainly shown in Fig. 4, and the ends of the battens 15 extend into guideways 16 attached to the sides of the window frame or casing 12. Each of the 80 guideways 16 is preferably made tubular with a guide slot 17 at the inner side for the passage of the corresponding ends of the battens 15, and the terminals of the battens 15 are preferably provided with friction 85 rollers 18 bearing against the inner face of the inner side of a guideway 16 (see Fig. 4) to insure an easy up and down movement 90 of the screen 14. One of the battens 15 is arranged at the bottom of the screen 14 and in each end of this batten 15 is mounted a catch 20 adapted to slide lengthwise of the batten. Each spring catch 20 is provided with a handle 21 adapted to be taken hold of by the operator, and the spring catch 95

is pressed on by a spring 22 to normally project the outer beveled end 23 beyond the corresponding end of the batten. This outer beveled end 23 is adapted to engage a spring keeper 24 secured to the corresponding 100 guideway 16 at the inside thereof (see Fig. 1) and this spring keeper 24 is so arranged that when the catch 23 engages the keeper then the bottom batten 15 is in contact with the sill of the window frame. In order to 105 insure a very firm contact between this bottom batten 15 and the sill, use is preferably made of a strip of rubber or other similar material 25, inserted between the two members of the bottom batten at the under side 110 thereof, as plainly indicated in Fig. 7.

When the screen 14 is in extended posi-

tion it reaches from the top of the window frame to the sill thereof, and as it extends into the guideways 16 attached to the sides of the casing, it is evident that this entire 5 window is covered to properly exclude insects and the like.

A guide roller 30 is journaled in the brackets 10 a distance below the roller 13 and farther inward so as to guide the screen 14 to the guideways 16, as will be readily understood by reference to Figs. 2 and 6. When it is desired not to use the screen, the operator presses the handles 21 of the spring catches 20 inward to disengage the outer 10 ends 23 thereof from the keepers 24, and then the operator allows the screen to slide upward and wind up on its spring-actuated roller 13. When the screen is rolled up convenient access is had to the window sashes to 15 permit of conveniently opening and closing the same, and when it is desired to again use the screen it is only necessary to pull it to lowermost position so that the spring catches 20 reengage the keepers 24 and thus lock 25 the screen in lowermost position against the tension of the usual spring in the roller 13.

In order to protect the screen when wound up on its roller 13, use is made of a casing 40, preferably of sheet metal, and open at 30 the back, as plainly indicated in Figs. 2 and 3. The bottom 41 of this casing 40 is adapted to fit into a guideway 42 formed transversely on the inner face of each bracket 10, and the top 43 of the casing 40 35 fits into similar guideways 44 formed on the inner faces of the brackets 10. The guideways 44 are inclined upwardly and rearwardly so that when the top 43 is engaged with the guideways 44 and the bottom 41 is 40 engaged with the guideways 42 then the casing is held securely in place on the brackets but can be readily removed therefrom whenever it is desired to do so. The brackets 10 may be attached to the top of the window 45 frame, as plainly shown in Fig. 1, or to the inner faces of the sides immediately below the top, as plainly shown in Fig. 6.

In the construction disclosed in Figs. 1, 2 and 3, the brackets 10 are provided with 50 bearings 50 for supporting a curtain pole 51, and the brackets are also provided with depending bearings 52 for supporting the roller 53 of the shade 54 so that special brackets for the shade roller and the curtain 55 pole are not necessary.

When using the brackets below the top at the inner faces of the sides of the frame, then the supports 50 for the curtain pole are dispensed with and the brackets are provided with bearings 52 for the roller 53 of the window shade 54, as will be readily understood by reference to Fig. 6.

The roll screen shown and described is very simple and durable in construction and

composed of comparatively few parts which 65 can be readily placed in position on the window frame, as above described.

Having thus described my invention, I claim as new and desire to secure by Letters Patent:—

1. A roll screen for windows, comprising brackets adapted to be attached to the window frame at the sides thereof, a spring-actuated roller journaled in the said brackets, a screen winding and unwinding on the said 75 roller and provided with a plurality of spaced battens, one of which is at the bottom of the screen, and others having friction rollers at their ends, tubular guideways attached to the sides of the window frame 80 and engaged by the said friction rollers at the ends of the said battens, manually controlled catches mounted in the ends of the said bottom batten, and keepers in the lower ends of the said guideways and adapted to be 85 engaged by the said catches to lock the screen in lowermost position.

2. A roll screen for windows, comprising brackets adapted to be attached to the window frame at the sides thereof, a spring-actuated roller journaled in the said brackets, a screen winding and unwinding on the said roller and provided with spaced battens, one of which is at the bottom of the screen, guideways attached to the sides of 90 the window frame and engaged by the ends of the said battens, manually controlled catches mounted in the ends of the said bottom batten, keepers in the lower ends of the said guideways and adapted to be engaged 95 by the said catches to lock the screen in lowermost position, and an elastic strip attached to the under side of the said bottom batten and adapted to engage the window sill at the time the said catches engage the 100 keepers.

3. A roll screen for windows, comprising a casing open at the back, brackets adapted to be attached to the window frame at the sides thereof, the brackets having supporting means for the said casing, a guide roller journaled on the said brackets within the lower portion of the casing, a spring-actuated screen roller journaled on the said 110 brackets above the said guide roller, a screen winding and unwinding on the said screen roller and passing over the rear of the said guide roller, the said screen being provided with spaced battens, of which one is at the bottom of the screen, tubular guideways 115 adapted to be attached to the sides of the window frame and having vertical guide slots at their inner sides, the ends of the said battens extending through the said guide slots of the guideways, manually controlled spring-pressed catches mounted in the end portions of the said bottom batten 120 and projecting beyond the ends thereof, and 125

spring keepers attached to the inside of the guideways near the lower ends thereof to be engaged by the said spring catches to lock the bottom batten in lowermost position.

5 4. In a device of the character described, the combination with a pair of brackets adapted to be attached to a window frame

and spaced apart and supporting a roller and screen thereon, horizontally disposed guideways on the inner faces of said brackets, 10 and an open back casing removably held by said guideways to inclose and protect the said screen roller and screen.

DAVID EDWARDS.
